CONTAINER COVER

David L. Chen, Brooklyn, N. Y.

Application December 31, 1938, Serial No. 248,672

1 Claim. (CL 217—56)

This invention relates to discardable covers for bottle containers.

Bottled drinks are frequently sold in cases or containers made of wood and having longitudinal and transverse partitions providing spaces to receive the bottles. The upper portions of the bottles are thus exposed, and when the bottles contain ale, the flavor of the same is often spoiled if daylight strikes it for even a few minutes. 10 Hence I have devised a cover for the bottles to prevent spoilage of the ale by exposure, and also to keep the bottles clean. Moreover, the cover is adapted to contain advertising matter concerning the drink and the brand name, and thus constitutes an interchangeable advertisement for use with different cases or containers.

A problem that confronted me was to find a proper method for the cheap and rapid attachment of the cover to the bottles or container 20 thereof. The bottles themselves are inserted into the case manually, the operator grasping a few bottles in each hand and with several rapid motions can insert two dozen bottles into a case. The cover itself must be similarly capable of very 25 rapid, convenient and reliable securement with only a few simple motions. Since the cases are supplied to a central shipping point along inclined chutes or conveyors, they travel at high speed and are subject to impact at certain points 30 or turns of the chute, and hence the covers will be knocked off unless properly attached. The cases themselves are preferably of standard shape and construction, and being cheaply made, are frequently considerably warped because the 35 wood thereof is insufficiently kiln dried.

I have attempted to provide a necessarily cheap cover, consisting of ordinary paper or cardboard, tucked in around some of the bottles, but have found that the cover is easily knocked 40 off. I then attempted to secure the cover directly to the bottle necks below the conventional heads or caps thereof, and though I provided holes of various sizes and shapes for this purpose, I nevertheless found that the cover would either 45 tear at the holes or would not hold with sufficient tightness for the intended purpose. It will be remembered that in all cases the cover must be adapted to be applied to the bottles at high speed; and that the bottles are loose in a warped 50 case, and hence may vary in position, spacing and in vertical relationship. It was only when I had devised a cover of the type herein disclosed, that a satisfactory solution of the problem was found.

55 The object of the invention is, therefore, to

provide a device of the character described which shall overcome the defects hereinbefore mentioned.

Another object of the invention is the provision of a device of the nature set forth having relatively few and simple parts, and which is durable, reliable, and efficient in use.

Other objects of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by 15 the same reference characters throughout the several views.

In the drawing:

Fig. 1 is a perspective isometric view of a device embodying the invention.

Fig. 2 is a vertical sectional view taken on the line 2—2 of Fig. 3, and showing a device embodying the invention with the cover applied.

Fig. 3 is a top plan view of the same.

Fig. 4 is a full size fragmentary top plan view 25 of the cover.

Fig. 5 is a sectional view of the cover taken on the line 5—5 of Fig. 4, but showing the same applied to a bottle.

The advantages of the invention as here outlined are best realized when all of its features and instrumentalities are combined in one and the same structure, but, useful devices may be produced embodying less than the whole.

It will be obvious to those skilled in the art to 35 which the invention appertains, that the same may be incorporated in several different constructions. The accompanying drawing, therefore, is submitted merely as showing the preferred exemplification of the invention.

Referring in detail to the drawing, 10 denotes 40 a device embodying the invention. The same may include a one-piece sheet of Kraft lined cardboard or other resilient material that possesses the required strength. The said cardboard may have a thickness of approximately 030 U. S. Standard gage, and may have a weight between 100 and 105 pounds per 1000 square feet. Its strength is indicated in that it requires a weight of 135 pounds to break it, according to 50 the Mullin test.

The device 10 may have generally circular bottle engaging holes 11 at the corners thereof. Each of these holes may have a series of radial slits 12 that are angularly spaced therearound.

The holes and the slits are in spaced relation to the end and side edges 13, 14 of the cover 10. Each of the holes has preferably eight slits arranged 45 degrees apart. The slits 12 provide 5 tongues 16 for engaging under the caps of the bottles. In Figs. 4 and 5 the arrangement and construction is shown in full size.

The main body of the cover 10 may carry advertising 17 and other pertinent indicia 18 10 relative to the bottled product. The general shape of the cover 10 is rectangular or such as to conform to the case that contains the bottles.

In Figs. 2 and 3 is shown a device embodying the invention and including a case 21 constructed 15 of wood or the like and having bottom, side and end walls 22, 23 and 24 respectively, interconnected by spaced longitudinal and transverse partitions 25, 26 respectively. These partitions provide spaces for receiving any conventional 20 bottles 27 that may have the well-known type of metallic closure caps 28 crimped at 29 under a lip of the rim of the bottle neck.

The cover 10 is engaged with the corner bottles as shown, the necks of the bottles extending 25 through the holes 11, with the tongues 16 engaged under the crimped cap portion 29, and the cover extending over all the intermediate bottles as is clearly shown in Fig. 2.

The cover is applied in the following manner. 30 As the case 20 filled with the bottles 27 comes along the conveyor, the operator places a cover 10 over the case, and applies pressure to the relatively stiff cover at the points indicated by the arrows 30 in Fig. 2, causing the convex top face 35 of the cap to spring the tongues 16 upward so that the caps pass through the holes 11, and the tongues then deflect back into the plane of the cover 10 and engage under the caps 28. The cover is thus securely connected, with the legends 40 17, 18 exposed to view, and with the cover fit-

ting in the case 21. In fact, the deformity produced in the cover in passing upward and over the bottles adjacent to the holes 11, aids in maintaining certain of the tongues 16 in tight fitted engagement with the caps 28. The cover thus 5 fully covers the bottles against exposure to daylight, and the case can be subjected to severe impact without knocking the cover loose.

It will be appreciated that the invention is not limited to the particular bottle cap or case disclosed, these being shown illustratively only and that any resilient or pliable board having sufficient stiffness and strength, preferably 100 pounds or more by the Mullin test may be employed. 10 15

It will be appreciated that various changes and modifications may be made in the device as shown in the drawing, and that the same is submitted in an illustrative and not in a limiting sense, the scope of the invention being defined in 20 the following claim.

I claim:

A device including an open top rectangular case filled with similar bottles all of which have 25 necks and closure caps, said bottles being positioned side by side with the tops of the caps in a common plane, a rectangular cardboard cover of substantially the size of the open top positioned in said case and supported solely by said 30 bottles and covering the same, said cover having at each of its four corners a substantially circular opening with radial slits thereabout, the remainder of said cover being imperforate, said cover being positioned in the box to rest upon the caps of all the bottles except of the four corner 35 bottles, said cover being locked in position by engagement of the caps of the four corner bottles in the adjacent respective corner openings of the cover.

DAVID L. COHEN. 40
